TWO TEMPERATURE REFRIGERATING APPARATUS

James W. Jacobs, Dayton, Ohio, assignor to General Motors Corporation, Detroit, Mich., a corporation of Delaware

Application December 13, 1952, Serial No. 325,813

6 Claims. (Cl. 62—117.3)

This invention relates to refrigerating apparatus and particularly to a primary refrigerating system having a closed secondary refrigerating system associated therewith and rendered effective thereby.

An object of my invention is to provide a double refrigerating system wherein the temperature of the evaporating portion of a closed secondary refrigerating system associated with a primary refrigerating system is intermittently and successively varied over a relatively wide temperature range.

Another object of my invention is to provide a closed secondary refrigerating system with a siphoning means or device which is rendered effective automatically by refrigerant in the system to cause the evaporating portion thereof to at one time attain a temperature below freezing and at another time to be increased to a temperature above freezing.

A further object of my invention is to provide means rendered effective automatically by refrigerant contained in a closed secondary refrigerating system associated with a primary refrigerating system to cause the evaporating portion of the secondary system to intermittently and successively function at a temperature whereby frost or ice will accumulate thereon and at a higher temperature to defrost the frost or ice therefrom.

It is a still further and more specific object of my invention to provide means for defrosting the evaporator utilized to cool the interior of an unfrozen food storage compartment of a refrigerator cabinet on which frost normally accumulates while maintaining the evaporator employed to cool a frozen food storage compartment in the cabinet below freezing at all times.

Other objects and advantages of the present invention will be apparent from the following description, reference being had to the accompanying drawing, wherein a preferred form of the present invention is clearly shown.

The figure in the drawing is a perspective view showing somewhat diagrammatically a refrigerator constructed in accordance with my invention and having parts thereof broken away.

Referring now to the drawing, reference numeral 10 designates the outer shell of a refrigerator cabinet having a metal liner 11 forming a freezing or frozen food storage compartment 12 and another metal liner 13 forming a main or unfrozen food storage compartment 14 therein. Suitable insulating material 16, interposed between shell 10 and the liners 11 and 13, surrounds the compartments and isolates one from the other. The refrigerator is of the multiple door type wherein a first door 17 is provided for closing the front opening to the freezing or frozen food compartment 12 and a second door 18 is provided for closing the front opening of the unfrozen food compartment 14. The invention is not restricted to the specific type of cabinet disclosed since it is equally applicable to a refrigerator in which a single door closes both compartments.

A primary refrigerating system is associated with the refrigerator cabinet 10 and includes a refrigerant transl-

ing unit comprising a motor-compressor (not shown), a condenser 21 and an evaporator 22. Evaporator 22 may be in the form of refrigerant expansion conduit loops wrapped around and secured to the outer surface of liner 11 for maintaining the frozen food compartment 12 at a below freezing temperature. The condenser 21 is supported in a lower machine compartment in the cabinet 10 below main food compartment 14 for a purpose to be herein-after described. Motor-compressor unit of the primary refrigerating system may be cyclically operated in response to temperatures prevailing in compartment 12 by a thermostatically actuated electric switch as is usual or conventional in the art. A closed secondary refrigerating system is also associated with cabinet 10 and functions or is rendered effective by the refrigerating effect produced by the primary refrigerating means or evaporator 22. This secondary system includes a refrigerant condensing portion or conduit 26 disposed in intimate heat exchange relationship with the primary evaporator 22. The secondary system also includes a refrigerant evaporating portion in the form of conduit passages 27 provided in superimposed and welded together sheet metal plates as is now conventional in the art. Plate secondary evaporator 27 is mounted, in any suitable or desirable manner, within the main unfrozen food storage compartment 14 and exposed to the air therein. A pipe or conduit 28 connects the outlet of passages 27 with the condensing conduit portion 26 of the secondary refrigerating system. A restricting means in the form of a small diameter pipe or conduit 29 connects the outlet of refrigerant condensing conduit portion 26 of the secondary system with a tank 31 disposed in the insulating material 16 of cabinet 10. Another pipe or conduit 32 is connected to the inlet of the passages 27 of secondary plate evaporator and enters the tank 31 at a substantial distance above the bottom thereof. The open end of pipe 32 is disposed near the bottom of tank 31. The arrangement of pipe 32 and the disposition of its open end, communicating with the interior of tank 31, forms a siphoning means or device in the closed circuit of the secondary refrigerating system intermediate the refrigerant condensing portion 26 and the refrigerant evaporating portion 27 thereof and is rendered effective automatically by refrigerant in this system in a manner and for a purpose to be presently described.

A trough 36 is provided directly beneath the secondary plate evaporator portion 27 and serves to direct water dripping therefrom down along a wall of compartment 14 whereby the water will flow into a drain opening 37 provided in the bottom wall of compartment 14. The drain opening 37 discharges the water into a condensate evaporating pan 38 mounted upon the refrigerant condenser 21 of the primary refrigerating system. Pan 38 is preferably in intimate heat exchange relationship with condenser 21 so that heat generated by this condenser will cause water in pan 38 to be vaporized into the condenser air stream. Such disposal of condensate water is now well known to those skilled in the art.

As before stated the evaporator 22 of the primary refrigerating system is adapted to maintain the interior of frozen food compartment 12 at a substantially constant low temperature, say for example, between 5° and 15° F. The secondary refrigerating system is calibrated and associated with the primary refrigerating system in such a way as to cause the evaporating portion or plate 27 thereof to at times fall below freezing temperature. The below freezing temperature of secondary evaporating portion 27 causes the same to withdraw moisture from the air in compartment 14 and deposit this moisture upon the same in the form of frost or ice. In accordance with my invention it is desired to provide an automatic defrost cycle in the operation of the secondary refrigerating system in order to clear frost or ice from evaporator 27 and render this

evaporator more efficient in cooling compartment 14. In order to intermittently and successively cause automatic defrost cycles for the refrigerant evaporating portion of the secondary system I provide this system with a quantity of refrigerant slightly greater than the capacity of the trapping tank or siphoning device 31.

When the refrigerator is placed in operation to reduce the temperature of the primary evaporator to between the temperature limits given, for example, refrigerant contained in the secondary refrigerating system evaporates in the evaporating portions 27 thereof and flows into the condensing portion 26 where it is cooled by the primary evaporator 22 and liquefied. Refrigerant vaporizing in the evaporating portions 27 of the secondary refrigerating system causes this plate evaporator to be reduced to a temperature below freezing whereupon frost or ice accumulates thereon. Refrigerant condensed in the condensing portion 26 of the secondary system flows therefrom into tank 31 through the restricting tube or pipe 29. This liquid refrigerant slowly drains into the siphon tank 31 wherein it is temporarily trapped. Finally the evaporating portion or plate 27 is starved of liquid refrigerant and its temperature begins to rise. This evaporating portion 27 of the secondary system rises in temperature above freezing before the siphoning means is rendered effective and frost or ice on the secondary evaporator melts therefrom then flows, by way of trough 36 and drain opening 37, into the defrost water evaporating pan 38. Shortly after the temperature of secondary evaporator 27 has risen above freezing the liquid level of refrigerant trapped and accumulating in siphoning tank 31 increases to a point above the uppermost part of conduit or pipe 32. This increase in the level of refrigerant in tank 31 renders the siphoning device operative. Tank 31 holds or contains a predetermined amount of liquid refrigerant prior to rendering the siphoning means operative and an increase of more than this predetermined accumulation of liquid refrigerant therein thus renders the siphoning device effective automatically for substantially emptying liquid refrigerant from tank 31 and quickly dumping the same into the evaporating portion 27 of the secondary refrigerating system. This evaporating portion of the secondary refrigerating system again functions to produce a below freezing temperature thereof. Liquid refrigerant dumped into evaporator 27 absorbs heat from compartment 14, evaporates and recondenses in the condenser 26 to thus start another cycle of intermittent and successive cycles of above freezing and below freezing temperatures of the secondary evaporator to periodically clear frost or ice therefrom.

It should be apparent from the foregoing that I have provided a novel apparatus for and method of intermittently and successively defrosting the evaporator of a secondary refrigerating system. I accomplish this desideratum without employment of moving parts, since the siphoning device is rendered effective automatically by refrigerant in the system, and therefore retain the secondary refrigerating system in as simple and inexpensive form as is possible. My invention provides for the defrosting of the refrigerant evaporating portion of a secondary refrigerating system without materially increasing the temperature of the cooling means or evaporator of a primary refrigerating system associated therewith and utilized to render the same operative. Thus an improved refrigerator of the type having a substantially constant low temperature freezing or frozen food storage compartment and a higher temperature main or unfrozen food compartment therein is provided.

While the form of embodiment of the invention as herein disclosed constitutes a preferred form, it is to be understood that other forms might be adopted, as may come within the scope of the claims which follow.

What is claimed is as follows:

1. In combination, a primary refrigerating system including a refrigerant translating unit and an evaporator,

a closed secondary refrigerating system containing a volatile refrigerant and including a refrigerant condensing portion in heat exchange relationship with said primary evaporator, a refrigerant evaporating portion, a conduit for conveying refrigerant evaporated in said evaporating portion into said condensing portion and means interposed between said portions for conveying refrigerant liquefied in said condensing portion into said evaporating portion and for causing said evaporating portion to produce a temperature below 32° F. and above 32° F. alternatively, said means comprising a siphoning device and a fixed restrictor for restricting flow of liquid refrigerant from the condensing portion of said secondary system into said siphoning device, said siphoning device receiving a predetermined amount of liquid refrigerant from said condensing portion of the secondary system and trapping the same therein, said siphoning device being rendered effective in response to an accumulation of more than said predetermined amount of liquid refrigerant therein for dumping substantially all of said trapped liquid refrigerant into the evaporating portion of said secondary system whereby its temperature falls below 32° F. and moisture deposits thereon in the form of frost or ice, and said restrictor delaying the accumulation of said more than said predetermined amount of liquid refrigerant in said siphoning device whereby the temperature of said evaporating portion of the secondary refrigerating system rises above 32° F. for defrosting the frost or ice therefrom.

2. In combination, a refrigerator cabinet, a frozen food storage compartment within said cabinet, a primary refrigerating system associated with said cabinet including a refrigerant translating unit and a freezing evaporator for cooling said frozen food compartment, an unfrozen food storage compartment within said cabinet, a closed secondary refrigerating system containing a volatile refrigerant and including a refrigerant condensing portion in heat exchange relationship with said primary evaporator, a refrigerant evaporating portion disposed within said unfrozen food compartment and exposed to air therein for cooling same, a conduit for conveying refrigerant evaporated in said evaporating portion into said condensing portion and means interposed between said portions for conveying refrigerant liquefied in said condensing portion into said evaporating portion and for causing said evaporating portion to produce a temperature below 32° F. and above 32° F. alternatively, said means comprising a siphoning device and a fixed restrictor for restricting flow of liquid refrigerant from the condensing portion of said secondary system into said siphoning device, said siphoning device receiving a predetermined amount of liquid refrigerant from said condensing portion of the secondary system and trapping the same therein, said siphoning device being rendered effective automatically in response to an accumulation of more than said predetermined amount of liquid refrigerant therein for dumping substantially all of said trapped liquid refrigerant into the evaporating portion of said secondary system whereby its temperature falls below 32° F. and moisture is withdrawn from air in said unfrozen food compartment and deposits thereon in the form of frost or ice, and said restrictor delaying the accumulation of said more than said predetermined amount of refrigerant in said siphoning device whereby the temperature of said evaporating portion of the secondary refrigerating system rises above 32° F. for defrosting the frost or ice therefrom.

3. The combination defined in claim 2 wherein a means is provided to convey the defrost water out of the unfrozen food storage compartment.

4. In combination, a primary refrigerating system including a refrigerant translating unit and an evaporator, a closed secondary refrigerating system having a refrigerant condensing portion in heat exchange relationship with said primary evaporator and a refrigerant evaporating portion, means for causing said evaporating portion of the secondary refrigerating system to alternatively produce a tem-

perature below and above 32° F., said means comprising an insulated unheated siphoning device interposed in the secondary system between said condensing and said evaporating portions thereof, said siphoning device receiving a part of the total amount of refrigerant in said secondary system from the condensing portion thereof and trapping the same up to a predetermined level therein, said siphoning device being rendered effective solely by an increase in the level of refrigerant received therein from the remainder of the amount thereof in said secondary system, above said predetermined level for substantially emptying the trapped refrigerant therefrom and simultaneously feeding all of the same into said evaporating portion whereby its temperature falls below freezing and moisture deposits thereon in the form of frost or ice, and said siphoning device being ineffective for feeding refrigerant into said evaporating portion of the secondary refrigerating system during accumulation of refrigerant therein up to said predetermined level whereby the temperature of said evaporating portion rises above freezing and defrosts the frost or ice therefrom.

5. In combination, a refrigerator cabinet, a frozen food storage compartment within said cabinet, a primary refrigerating system associated with said cabinet including a refrigerant translating unit and a freezing evaporator for cooling said frozen food compartment, an unfrozen food storage compartment within said cabinet, insulating material around and between said compartments, a closed secondary refrigerating system having a refrigerant condensing portion in heat exchange relationship with said primary freezing evaporator and a refrigerant evaporating portion disposed within said unfrozen food compartment and exposed to air therein for cooling same, means for

causing said evaporating portion of the secondary refrigerating system to alternatively produce a temperature below and above 32° F., said means comprising an unheated siphoning device interposed between said condensing portion and said evaporating portions of the secondary refrigerating system and surrounded by said insulating material, said siphoning device receiving a part of the total amount of refrigerant in said secondary system from the condensing portion thereof and trapping the same up to a predetermined level therein, said siphoning device being rendered effective solely by an increase in the level of refrigerant received therein, from the remainder of the amount thereof in said secondary system, above said predetermined level for substantially emptying the trapped refrigerant therefrom and simultaneously feeding all of the same into said evaporating portion whereby its temperature falls below freezing and moisture is withdrawn from air in said unfrozen compartment and deposits thereon in the form of frost or ice, and said siphoning device being ineffective for feeding refrigerant into said evaporating portion of the secondary refrigerating system during accumulation of refrigerant therein up to said predetermined level whereby the temperature of said evaporating portion rises above freezing and defrosts the frost or ice therefrom.

10 6. The combination defined in claim 5 wherein a drain opening is provided in the unfrozen food storage compartment for conveying the defrost water out of the same.
